FOOD PACKAGING TRAY

Donald K. Jewell, Chicago, Ill., assignor to Lincoln
Manufacturing Company, Inc.

Filed Jan. 18, 1971, Ser. No. 107,616

Term of patent 14 years

Int. Cl. D9—03

U.S. Cl. D9—219

FIG. 1

FIG. 3

FIG. 1 is a bottom plan view of a food packaging tray showing my new design;

FIG. 2 is a top perspective view thereof showing one side and end, the opposite side and end being identical thereto; and

FIG. 3 is an enlarged section taken on line 3—3 of FIG. 1.

I claim:

The ornamental design for a food packaging tray, substantially as shown and described.
